UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

PIANO PLAYER.

1,409,479.

Specification of Letters Patent. Patented Mar. 14, 1922.

Application filed January 19, 1910, Serial No. 538,883. Renewed June 22, 1918. Serial No. 241,439.

To all whom it may concern:

Be it known that I, CHARLES F. STODDARD, a citizen of the United States, residing at New York, in the county of New York and 5 State of New York, have invented an Improvement in Piano Players, of which the following description, in connection with the accompanying drawings, is a specification, like letters on the drawings representing 10 ing like parts.

This invention relates to automatic means for playing musical instruments such as pianos; and pertains more particularly to means for governing and varying tone in- 15 tensities.

Among other objects; the invention is intended to provide apparatus capable of governing the energy used for sounding a tone or tones, as for striking the strings of a 20 piano; and the invention contemplates simple and stable, though accurate and effective, means to this end.

For illustration, the accompanying drawing shows one practicable embodiment of 25 the invention employing suitable pneumatically governed devices in cooperation with a piano action; but, as will appear to those skilled in the art, the invention is susceptible of embodiment in various constructions 30 and organizations other than that particularly shown and described herein.

In the drawing:

Fig. 1 is a diagrammatic representation of 35 a typical piano action, with operating and governing means embodying the invention;

Fig. 2 is a diagrammatic representation of 40 a perforated music sheet such as may be used in cooperation with the apparatus shown in Fig. 1.

Referring to the drawing, a typical piano 45 action, shown in its normal position of rest, comprises a key-controlled sticker B, to act on a wippen I, a hammer C, damper E, string D, and other parts which may be those well-known in the art. To operate the action 50 pneumatically a motor pneumatic F is provided, having a sticker H to act upon the wippen I. A wind trunk 7 leads to the wind chests of the motor pneumatics, each of which has a secondary valve 8, controlled by a primary valve 9 operated from the tracker bar G through a duct 10, in the usual manner.

The trunk 7 communicates with a regu-

lated exhaust chest 12. A high exhaust chest 55 14 arranged for communication with the chest 12, may be connected by a trunk 15 with any source of pneumatic exhaust, such as feeder bellows of any practicable type.

Between the high exhaust chest 14 and the 60 regulated exhaust chest 12 is a chamber 30, open at its lower extremity to the chest 14, and communicating with the chest 12 through suitable ports. The chamber 30 contains a piston valve 31, which governs com- 65 munication between the two chests so as to subject the regulated exhaust more or less to the influence of high exhaust.

The stem 32 of the valve 31 projects up- 70 wardly through the top of the chamber 30, into a cylinder of graduated diameter. Within the cylinder, in the illustrative em- bodiment shown, is a unitary piston of grad- uated diameter corresponding in shape to the 75 interior of the cylinder. Said piston com- prises the three superposed cylindrical parts 34, 35 and 36, presenting respectively the acting areas x, y and z.

A tension spring 37 connected to the pis- 80 ton stem 32, exerts an upward pull upon the latter. The tension of the spring may be adjusted or otherwise modified, as by a han- 85 dle 38, to vary the said upward pull as hereinafter explained; but for the present this capacity for modification may be neglected 85 and the upward pull by the spring may be considered substantially constant, disre- 90 garding the minute fluctuations in tension of the spring resulting from negligible elonga- 90 tion and contraction accompanying move- ment of the piston structure. This substan- tially uniform pull of the spring contributes to control the piston structure and valve 31 as presently described.

In discussing the various pneumatic in- 95 fluences brought to bear upon the piston structure, the so-called "exhaust" or "air ten- sion" will be treated as having a positive pressure relative to a perfect vacuum of zero pressure. This mode of treatment is more 100 convenient in explaining the operation of the piston structure than would be the case if exhaust were considered in the popular sense of exerting a pull by suction as distin- guished from a push by pressure.

Ducts 40, 41 and 42 enter respectively the 105 cylinder chambers opposite the piston faces x, y and z. Each duct is controlled (as here-

inafter explained) so as to admit to its cylinder chamber either atmospheric pressure, or regulated pressure from the chest 12; and the regulated pressure may be admitted to 5 any one or more, or all, of the chambers while atmospheric pressure will be present in those chambers, if any, which do not contain regulated pressure. These pressures within the cylinder chambers act upwardly 10 upon the piston faces x , y and z , and together with the upward pull of the spring 37, constitute the forces tending to move the piston structure upwardly. The high exhaust in chest 14 exerts some upward pressure 15 upon the piston valve 31, which is so minute as to be negligible in the specific apparatus under discussion.

These upwardly directed forces are opposed by atmospheric pressure acting downwardly 20 upon the interior of the piston structure, which is open to atmosphere through a port 43.

In the illustrative apparatus the upwardly exposed piston areas substantially equal the 25 downwardly exposed areas x , y and z . If, therefore, atmosphere be admitted to all the cylinder chambers, its upward pressure on the areas x , y and z will be opposed and balanced by equal downward pressure of atmosphere 30 upon equal areas. This leaves the spring 37 unopposed to lift the piston valve 31 and open the valve ports to the fullest extent thereby subjecting regulated pressure in the chest 12 to the maximum influence of 35 high exhaust in the chest 14. Under these conditions notes are sounded with maximum loudness.

When the present invention is embodied 40 in a construction which employs exhaust as distinguished from compressed air, the regulated exhaust or pressure is always less than atmospheric pressure. Consequently when regulated pressure is admitted to all the cylinder chambers, the upward pneumatic pressure on the piston structure is then 45 at its minimum, being, of course, less than when atmosphere is admitted to any one or more of the cylinder chambers. Downward atmospheric pressure, being thus opposed by 50 the minimum pneumatic upward pressure, substantially predominates and moves the piston structure downwardly, the spring 37 having its tension adjusted so that its upward pull will be overcome more or less by 55 said downward atmospheric pressure. This downward movement of the piston structure tends to close the valve ports between the chests 12 and 14 with the result that regulated pressure may be largely cut off from 60 the influence of high exhaust in the chest 14. Under these conditions, i. e. when regulated pressure is admitted to all the cylinder chambers, notes are played with minimum loudness available in the specific apparatus illustrated in the drawings.

It will be evident to those skilled in the art, that the greater the piston area exposed to regulated pressure, the greater will be the predominance of downwardly acting atmospheric pressure and the greater will be the 70 constriction of communication between the chests 12 and 14. In other words, the greater the piston area exposed to regulated pressure subjected to the influence of high exhaust and the less 75 will be the intensity of sounded notes. Accordingly, the general operation of the cylinder and piston structures described above may be conveniently summarized thus:— admitting regulated pressure to a cylinder 80 chamber diminishes intensity; admitting atmospheric pressure to a cylinder chamber increases intensity.

There is always some leakage of atmosphere to the chest 12 as, for instance, past 85 the various valve mechanisms and from the motor pneumatics, such leakage tending constantly to increase regulated pressure and actually increasing it unless the leakage be fully compensated by exhaust through the 90 chest 14 by way of the valve ports in the chamber 30. Under these circumstances, whenever the piston structure moves downwardly and thereby restricts the openings between the chests 12 and 14 the result is to 95 increase regulated pressure. This increase in regulated pressure is, of course, communicated practically instantaneously to those cylinder chambers which contain regulated pressure. Consequently, whenever the piston structure moves downwardly because of downward atmospheric pressure predominating over upward regulated pressure, the indirect result is to increase the upwardly acting regulated pressure and thereby to decrease the predominance of downward atmospheric pressure. The greater the extent of downward movement of the piston structure—the greater will be the described decrease in the predominance of downward 100 atmospheric pressure.

In any instance the piston structure will move downwardly until the predominance of downward atmospheric pressure diminishes to such an extent that the upward pull of the spring balances the diminished predominance of downward atmospheric pressure, whereupon the piston structure comes to rest.

In like manner, whenever the piston structure moves upwardly to enlarge the openings between the chests 12 and 14, the effect is to diminish regulated pressure by exhaust through the chest 14. This diminution in regulated pressure is communicated to those cylinder chambers which contain regulated pressure; and consequently the upward regulated pressure on the piston is diminished. In other words, the piston structure moves upwardly because of the predominance of 120 125 130 135 140

upward pneumatic pressure plus the pull of the spring; such upward movement of the piston structure has the effect of decreasing the predominance of upward pressure and 5 such decrease continues during upward movement of the piston structure until there is no longer any predominance and the opposed forces are balanced, whereupon the piston structure comes to rest.

10 In the operation of the specific illustrative apparatus, therefore, the piston structure is constantly under the control of opposed forces tending always to balance each other and hold the piston structure, as it 15 were, in suspension between them; that is to say, the specific apparatus tends constantly to establish a balancing equation between the opposed forces acting upon the piston. Such movement of the piston structure as 20 may occur when that balancing equation is disturbed, takes place practically instantaneously so that a new balancing equation appropriate to the newly initiated conditions is immediately set up.

25 The actual variation of regulated pressure may result from a number of causes, or a combination of causes, such that the piston structure and valve 31 may or may not be moved to assist in a re-establishment of the 30 pressure equation above referred to, which holds the piston structure at rest and in balance.

Normally, and even at a time when it is desired to maintain constant regulated pressure, some leakage of atmosphere to the chest 35 12, and various parts communicating therewith, may tend to reduce the regulated tension in said chest, whether or not any of the motor pneumatics F is in action. A reduction 40 in regulated tension from such cause may be compensated to some extent by leakage between the high tension chest 14 and the chest 12, as by leakage past the piston valve 31. If, however, regulated pressure 45 increases enough to disturb a prevailing pressure equation, there may result an upward movement of the piston structure, enlarging the openings between the chests 12 and 14 enough to permit high exhaust to 50 restore the intended regulated pressure in chest 12. Such action takes place so promptly and quickly, that, in effect, it serves to maintain regulated tension substantially constant (until intentionally ad- 55 justed), rather than to restore it.

Each motor pneumatic F, when idle, contains atmosphere which tends to increase regulated pressure in the chest 12, when the pneumatic is thrown into operation. Obviously, if several motor pneumatics F act simultaneously there may be a considerable increase of regulated pressure. Ordinarily, in the operation of the illustrative apparatus, the regulated pressure may be thus subjected to frequent fluctuations by the action

of the motor pneumatics. Whenever such fluctuation so increases regulated pressure that a pressure equation is disturbed, the piston valve 31 may be moved to restore the equation as described. As already suggested, this restoring action takes place so quickly that it is rather a maintaining action in respect to its general effect upon the regulated pressure.

From the above it appears that whatever 75 draughts are made upon the regulated pressure chest 12, from whatever cause, said pressure may be maintained always by the described balancing operation of the piston structure controlling communication between 80 the chests 12 and 14. Immediately, however, when a deliberate, intentional change is made in the piston area exposed to regulated pressure, the pressure equation is temporarily disturbed, to be restored when a new 85 and different regulated pressure is established.

It will be noted that the regulating action of the piston structure may serve merely to maintain the desired regulated pressure in 90 spite of any drafts made thereupon, as for instance, by the motor pneumatics. That is to say, the regulation does not necessarily result from varying communication between the high exhaust chest and the regulated 95 pressure chest. For instance, assume that the piston area acted upon by regulated pressure be so changed that a considerable increase in regulated pressure is demanded to re-establish the pressure equation. Assume further that this change in piston area be accompanied by the action of a considerable number of motor pneumatics F, which in effect alone suffices to increase the regulated pressure so as to re-establish the 100 balancing pressure equation. Under such circumstances regulated pressure is changed from a lower to a higher working level without making necessary any change in the communication between the two chests 12 and 105 14. Thus in greater or less degree, the mere utilization of regulated pressure in the chest 12, may cooperate with the deliberate variations of piston area acted upon by the regulated pressure, so that the control of communication between the chests exercised by the piston valve may be, and frequently it will be, of supplemental and auxiliary 110 effect.

Hereinbefore a preferred form of regulating mechanism has been described. The manner in which the same may be governed to initiate different regulated tensions will be next explained.

Referring again to the drawing, the duct 125 40 connects the cylinder chamber opposite the piston area x with a valve chamber 49. In said chamber is a duplex valve 50, arranged for opening an upper port to atmosphere and alternatively opening a port from 130

the chamber 49 through a duct 51 to the regulated tension chest 12. The valve 50 is controlled by a diaphragm over a chamber 54 which communicates with a duct 56. A duplex valve 58 controls a port from the duct 56 to atmosphere, and a second port from the duct 56 to a chamber 59 communicating by a duct 60 with the high exhaust chest 14. The valve 58 is controlled by a diaphragm 10 over a chamber 62 which communicates by a duct 63 with a tracker vent T.

When the tracker vent T is open the diaphragm of chamber 62 is distended and the valve 58 elevated so as to vent the diaphragm 15 chamber 54 to atmosphere and distend its diaphragm to elevate the valve 50 and vent the duct 40 to atmosphere. The converse of this operation which closes the duct 40 to atmosphere and opens it to regulated tension 20 will be described hereinafter.

The parts just described are triplicated for controlling the ducts 41 and 42, the corresponding parts of the valve mechanism for the latter being indicated by the numerals 50, 51, etc., with indices a for the valve mechanism for duct 41, and b for the valve mechanism for duct 42.

In the valve mechanism for duct 41 it is assumed that the duct 63^a to the tracker 30 vent T^a is open to atmosphere which distends the diaphragm of chamber 62^a, venting chamber 54^a to atmosphere and admitting atmosphere to the duct 41, past the valve 50^a and to the cylinder chamber opposite the piston surface y. Thus, whenever 35 a tracker vent T, T^a or T^b, is open, atmosphere is admitted to the corresponding cylinder chamber.

When one of the valves 50, 50^a, 50^b, is once opened by venting the corresponding tracker duct, the valve preferably continues open even though the tracker vent may be immediately closed. In the specific apparatus this results from the fact that once 45 the valve 58^a, for instance, is opened to admit atmosphere to the diaphragm chamber 54^a, said valve 58^a is held in that position by atmosphere admitted past the valve 58^a into a duct 70^a through a bleeder vent 72^a, 50 and a duct 74^a (shown in dotted lines), which latter communicates with the diaphragm chamber 62^a. The chamber 59^a above the diaphragm communicates as described with the high exhaust chest 14. 55 Thus so long as atmosphere is admitted through duct 70^a to duct 74^a the diaphragm of chamber 62^a will remain distended and atmosphere will continue in the corresponding cylinder chamber y. The parts just described as pertaining to the valve 50^a are duplicated to cooperate with the valves 50 and 50^b.

From the preceding discussion it will appear that small perforations in a music 65 sheet may be employed to open the tracker

vents T, T^a, and T^b which may be immediately closed if desired. When used with the illustrative apparatus, each such perforation has the effect of introducing atmosphere to a cylinder chamber, and even 70 after the tracker vent is closed, atmosphere will continue in the cylinder chamber until purposely exhausted at any desired subsequent time in a manner such as that about to be described. 75

The specific apparatus shown in the drawings comprises a single valve mechanism, controlled by a single tracker vent, which may cooperate with all or any of the three above described valve mechanisms, to negative the effect of opening one or more of the tracker vents T, T^a and T^b. This single valve mechanism is shown at the right of Fig. 1. 80

A tracker vent R communicates by its 85 duct 80 with a diaphragm chamber 82. The latter controls a duplex valve 84 which in its alternative positions admits atmosphere to a duct 86 or opens communication between said duct 86 and a duct 88 leading 90 to the high exhaust chest 14. An extension of the duct 86 communicates with each of the three diaphragm chambers 90, 90^a and 90^b. Thus when atmosphere is admitted to the duct 86, past the valve 84, the diaphragms of the chambers 90, 90^a, and 90^b are distended. In describing the effect of this operation, it is convenient to refer to chamber 90^a and associated parts. 95

As already stated, the valve 58^a is held 100 in the open position shown, by the fact that atmosphere is present in the ducts 70^a and 74^a. When, however, the diaphragm of chamber 90^a is distended, it lifts a disk valve 92^a and closes communication between 105 duct 70^a and duct 74^a, thereby closing the latter from atmosphere. At the same time the valve 92^a opens communication between the duct 74^a through the bleeder 72^a, with chamber 94^a which is open to high exhaust 110 through the duct 60^a. In this manner the duct 74^a is connected with high exhaust which bleeds the atmosphere from chamber 62^a thereby permitting valve 58^a to drop, shutting off atmosphere from the diaphragm chamber 54^a and throwing the latter into communication with the chamber 59^a and the high exhaust chest 14 through the duct 60^a. When the diaphragm chamber 54^a is thus exhausted by high exhaust, 115 the valve 50^a is permitted to drop shutting off atmosphere from the cylinder duct 41 and throwing the latter into communication with the duct 51^a leading to the regulated pressure chest 12. In this manner, merely 120 by opening the tracker vent R, the duct 41 and its cylinder chamber y are closed to atmosphere and opened to regulated pressure. 125

The operation just described, so far as 130

concerns the specific illustrative mechanism, depends upon bleeding the diaphragm chamber 62^a. If the tracker duct 63^a be open through its vent T^a, at the time the 5 vent R is opened to initiate the bleeding of diaphragm chamber 62^a, atmosphere will enter the chamber 62^a more rapidly than it can be exhausted therefrom by the described bleeding; therefore the effect of 10 opening the vent R is negated, and in such circumstances that valve 58^a will remain open and atmosphere will continue in the corresponding cylinder chamber.

Also if the tracker vent T, for instance, 15 be open simultaneously, with the tracker vent R, the latter will inaugurate a tendency to bleed the chamber 62 and keep the valve 58 closed in the position shown, but the simultaneous opening of the tracker vent T 20 will admit atmosphere to the chamber 62 more rapidly than it can be exhausted by bleeding and therefore the valve 58 will be lifted in spite of the opening of the tracker vent R.

25 From the above description it will be understood that whether or not the tracker vent R be open, the opening of any of the vents T, T^a, T^b, will have its normal and usual effect to admit atmosphere to the appropriate chamber or chambers of the cylinder. This will be true if any vent T, T^a, T^b, be opened with or without simultaneously opening the tracker vent R.

30 On the other hand, if the vent T^a be opened and then closed (atmosphere being thereby admitted to a cylinder chamber) and the vent R be thereafter opened, the previous effect of opening vent T^a will be negated and the cylinder chamber opened 40 to regulated pressure.

35 The effect of opening and closing the various tracker ducts in the specific mechanism may be readily understood by referring to an illustrative form of perforated music 45 sheet diagrammed in Fig. 2 in which are shown four lines of perforations for governing the expression controlling tracker vents. The music sheet may be assumed to be traveling in the direction of the arrow in Fig. 2. The tracker G is shown in dotted lines in Fig. 2, the vent T^a being open through the perforation 100 in the sheet. All the other vents are closed. The perforations in the sheet for operating the motor pneumatics 50 may be disregarded for brevity.

55 When the note sheet and tracker are related as shown in Fig. 2, the various valve mechanisms occupy exactly the positions shown in Fig. 1. If now the music sheet 60 progresses in the direction of the arrow, perforation 101 will presently open the vent R; this will distend the diaphragm of chamber 82; open the duct 86 to atmosphere; admit atmosphere to diaphragm chamber 90^a; lift valve 92^a; and throw the diaphragm cham-

ber 62^a in communication with the high exhaust chest 14, through the duct 74^a, past the bleeder 72^a, through the chamber 94^a and duct 60^a. This permits the valve 58^a to drop and thereby the diaphragm chamber 54^a is 70 exhausted as described, with the final result that the cylinder duct 41 and chamber y are closed to atmosphere and opened to regulated pressure. In these circumstances regulated pressure is present in all of the cylinder chambers. 75

When the music sheet progresses further the perforation 102 opens the vent T and, as will be understood, thereby opens the duct 40 and cylinder chamber x to atmosphere. 80 Thereafter a perforation 103 and a perforation 104 register respectively and simultaneously with the vents R and T^a. The perforation 103 negatives the previous effect of the perforation 102 and opens the cylinder 85 chamber x to regulated pressure. The perforation 103 is ineffective, however, in respect to perforation 104 which opens the vent T^a and thereby admits atmosphere to the cylinder chamber y. 90

As the note sheet progresses further, perforations 105 and 106 open the vents T and T^b which admit atmosphere to the cylinder chambers x and z. The previous effect of the perforation 104 endures, and therefore 95 by reason of the three perforations 104, 105 and 106 atmosphere is present in all of the cylinder chambers.

Next a perforation 107 opens the vent R and simultaneously a perforation 108 opens the vent T^a. The effect of the perforation 107 is to negative the previous effect of both the perforations 105 and 106 and to open the cylinder chambers x and z to regulated pressure. The perforation 107, however, is ineffective in respect to perforation 108 which merely continues the previously established effect of the perforation 104 leaving the cylinder chamber y still open to atmosphere. 105

Next perforations 109 and 110 reinstate 110 atmosphere in the cylinder chambers x and z and again all of the cylinder chambers are open to atmosphere.

Next a perforation 111 opens the vent R at a time when all the other vents are closed 115 and thereby negatives the effects of all three perforations 108, 109 and 110 with the result that all the cylinder chambers are closed to atmosphere and open to regulated pressure.

The preceding description will suffice to 120 indicate the variety of combinations of perforations whereby atmosphere and regulated pressure may be alternated in one or more of the cylinder chambers with the resultant variations in regulated pressure and in the 125 intensities of notes played thereby.

As will appear to those skilled in the art the usual note perforations may occur in the music sheet or may be related with the described expression-regulating perforations 130

in any practicable manner, as for instance by aligning or substantially aligning, the advance end of a note perforation with one or more expression perforations to establish 5 the regulated pressure in the chest 12 for playing the note with desired intensity.

- Reference may now be had to the spring 37 shown in Fig. 1. If this spring remain unadjusted with the substantially constant 10 tension which has been assumed up to the present time in this description, the various operations hereinbefore explained will determine desired relative and absolute intensities of notes automatically, so that without 15 any conscious or other regulation, a composition may be played entirely automatically with all the desired shades of expression predetermined by the arrangement of expression perforations on the music sheet 20 in relation to the note perforations. It may be desired, however, that some opportunity exist for consciously modifying the expression, as for instance by manual control; and by means of the mechanism in the drawings 25 or its equivalent, expression may be controlled altogether consciously, to the exclusion of automatic control; or the conscious control may merely modify the automatic control; or the control may be wholly automatic and without conscious governance. 30

For instance, a note sheet such as that diagrammed in Fig. 2, properly perforated to play a composition with desired expression, may control a complete automatic operation of the apparatus. At the same time, this automatic operation may be modified by varying the tension of the spring 37, as by means of the handle 38 suitably connected to the spring. This handle, or any equivalent or substitute agency, may be used or not as desired and consequently a composition may be played partly with automatic expression control and partly with consciously modified expression control. 45

For another example, the apparatus is susceptible of use with a music sheet having no expression perforations whatever so that the automatic control is dispensed with entirely. In such a case the cylinder chambers 50 may all contain atmosphere or may all contain regulated tension. Nevertheless, the piston valve 31 may be controlled through any suitable means as for instance, the spring 37.

In the operation of the described apparatus, communication between the high exhaust chest 14 and the regulated pressure chest 12 may be so restricted as to increase regulated pressure to such an extent that 60 that latter will not properly operate the motor pneumatics. To avoid this the apparatus shown in Fig. 1, may include a floating piston valve 115 mounted in a conduit entering the high exhaust chest 14 and communicating with the regulated pressure 65

chest 12 by a port 116. This valve 115 normally closes ports 117 in the conduit. The piston valve 115 is preferably governed by a spring 118 resting upon an abutment 119 adjustable to vary the tension of the spring 70 118 by means of a screw 120. The spring 118 holds the piston valve 115 normally seated against an interior shoulder of the conduit and in position to close ports 117. It will be seen that the upper surface of 75 the piston valve is exposed to regulated pressure; high exhaust is admitted to the lower surface of the piston valve through ports 121 in the conduit. It is evident that the greater downward pressure of regulated 80 pressure on the top of the valve is opposed by the less pressure of high exhaust on the bottom of the valve and also by the upward pressure of the spring on the bottom of the valve. The spring is so adjusted that its 85 pressure combined with that of high exhaust will hold the piston valve in position to close the ports 117 until regulated pressure increases to a certain maximum (i. e. its degree of exhaust is reduced to a certain 90 minimum) when the valve is depressed and opens communication between the two chests sufficiently to reduce the regulated pressure to a desired point. Obviously by means of the feature of adjustment exemplified by the 95 screw 120, the apparatus can be arranged so that the regulated pressure can never increase above a certain maximum; and by this means it is possible to arrange that no notes shall be played at less than a desired 100 intensity.

It is to be understood that this invention is not limited to the specific construction and organization described for illustration. On the contrary the described apparatus 105 may be variously changed, modified, and reorganized without departing from the scope of the invention as defined in the subjoined claims.

Claims.

1. An instrument of the character described comprising, in combination, playing actions; a main source of power for operating said playing actions; expression-governing means for varying by perceptible increments the degree of power applied to the playing actions; and supplementary expression-governing means for varying the degree of power applied to the playing actions by substantially continuous progression, said two 115 expression-governing means being constructed and arranged for concurrent operation. 120

2. An instrument of the character described comprising, in combination, playing actions; a main source of power for operating said playing actions; expression-governing means for varying the degree of power applied to the playing actions by perceptible increments; and manually operable additional expression-governing means to vary 130

the degree of power applied to the playing actions by substantially continuous progression.

3. An instrument of the character described comprising, in combination, playing actions; a main source of power for operating said playing actions; expression-governing means for varying the degree of power applied to the playing actions by perceptible increments; a tracker and means connected therewith for automatically controlling said expression-governing means; and additional manually operable expression-governing means for varying the degree of power applied to the playing actions by substantially continuous progression.

4. An instrument of the character described comprising, in combination, playing actions; a main source of power for operating said playing actions; expression-governing means for varying by perceptible increments the degree of power applied to said playing actions; and means for producing substantially continuous crescendo effects concurrently with variations by said expression-governing mechanism.

5. An instrument of the character described comprising, in combination, playing actions; a main source of power for operating said playing actions; regulating means for varying the degree of power applied to the playing actions; means to modify the regulating action thereof by perceptible increments to produce incremental changes in playing intensity; and additional means for varying said regulating action by substantially continuous progression.

6. An instrument of the character described comprising, in combination, playing actions; a main source of power for operating said playing actions; expression-governing means for varying the degree of power applied to the playing actions including means for applying opposed forces for controlling the said expression governing means; means for varying some of said forces to vary the degree of said power by perceptible increments; and means for varying some of said forces to vary said power by substantially continuous progression.

7. An instrument of the character described comprising, in combination, playing actions; a main source of power for operating said playing actions; a regulator, including a spring, for varying the degree of power applied to the playing actions; means for varying the regulating action thereof by perceptible increments; and means acting upon said spring to vary said regulation by substantially continuous progression.

8. An instrument of the character described, comprising, in combination, playing actions; a main source of power for operating said playing actions; means to control the degree of power applied to the playing actions;

and expression-governing apparatus cooperating with said means constructed and arranged to vary the degree of said power by substantially continuous progression and also by perceptible increments during such progression. 70

9. An instrument of the character described, comprising, in combination, playing actions; a main source of power for operating said playing actions; and expression-governing apparatus constructed and arranged to produce a crescendo and an incremental intensity change during the crescendo. 75

10. An instrument of the character described, comprising, in combination, playing actions; a main source of power for operating said playing actions; regulating means intermediate the playing actions and said source of power; and expression-governing means of varying the regulation thereby, constructed and arranged to produce a crescendo and incremental intensity changes during the crescendo. 80

11. An instrument of the character described, comprising, in combination, playing actions; a main source of power for operating said playing actions; expression-governing means to govern the degree of power applied to said playing actions; means to apply opposed forces tending to hold the expression-governing means in balance; means to vary the resultant of said opposed forces by perceptible increments; and means to vary said resultant by substantially continuous progression. 90

12. An instrument of the character described, comprising, in combination, playing actions; a main source of power for operating said playing actions; expression-governing means to govern the degree of power applied to said playing actions; means operatively connected with said expression-governing means constructed and arranged to produce opposed forces having a resultant for governing said expression-governing means; and expression-varying apparatus for varying said resultant incrementally or by substantially continuous progression or by a combination of the two. 105

13. An instrument of the character described, comprising, in combination, playing actions; a main source of power for operating said playing actions; a throttle valve for varying the degree of power applied to the playing actions; means for applying governing force to said throttle valve; and expression-governing apparatus for varying said force by perceptible increments or by substantially continuous progression; and separately operable controlling means for said expression-governing means. 120

14. An instrument of the character described, comprising, in combination, playing actions; a main source of power for operat- 125

ing said playing actions; regulating means having a variable area exposed to pneumatic pressure; means to vary such area so exposed to pneumatic pressure; and additional means to vary the regulation by said regulating means.

15. An instrument of the character described, comprising, in combination, playing actions; a main source of power for operating said playing actions; expression-governing means for varying the degree of power applied to said playing actions; a tracker; apparatus having connection with a plurality of tracker vents, to produce an increment of change in the degree of said power corresponding to each said tracker vent; and means having connection with a single tracker vent to negative such changes by said plurality of tracker vents.
16. An instrument of the character described comprising, in combination, playing actions; a main source of power for operating said playing actions; expression-governing means to vary the degree of power applied to said playing actions; a plurality of means operatively connected to said expression-governing means to produce a plurality of incremental changes in playing intensity; and a single means to negative operation of said plurality of means.

17. An instrument of the character described comprising, in combination, playing actions; a main source of power for operating said playing actions; expression-governing means to vary the degree of power applied to said playing actions; a plurality of means operatively connected to said expression-governing means to produce a plurality of incremental changes in playing intensity; a single means to negative operation of said plurality of means; a tracker; and controlling means connecting each of said plurality of means and said single means with a corresponding tracker vent.

18. An instrument of the character described comprising, in combination, playing actions; a main source of power for operating said playing actions; expression-governing means to vary the degree of power applied to said playing actions; a plurality of means operatively connected with said expression-governing means and operable singly or permutatively, for producing incremental changes in playing intensities; and a single means to negative operation of all said plurality of means.

19. An instrument of the character described comprising, in combination, playing actions; a main source of power for operating said playing actions; expression-governing means to vary the degree of power applied to said playing actions; a plurality of valve mechanisms for governing the expression-governing means, each valve mechanism being constructed and arranged to

produce an incremental change in playing intensity; means separately to control said valve mechanisms; and additional means for controlling said valve mechanisms, common to all thereof.

20. An instrument of the character described comprising, in combination, playing actions; a main source of power for operating said playing actions; expression-governing means to vary the degree of power applied to said playing actions; a plurality of valve mechanisms separately operable to govern the expression-governing means to produce different playing intensities; means for separately controlling said plurality of valve mechanisms; and another valve mechanism for controlling said plurality of valve mechanisms.

21. An instrument of the character described comprising, in combination, playing actions; a main source of power for operating said playing actions; means for varying the degree of power applied to said playing actions; a tracker having a plurality of vents corresponding each to an incremental change in playing intensity and a single tracker vent corresponding to the reverse of all said incremental changes; and means operatively connecting said tracker vents with the expression-governing means, constructed and arranged to produce said incremental changes by said plurality of tracker vents respectively, and to produce reverse changes by said single tracker vent.

22. An instrument of the character described comprising, in combination, playing actions; a main source of power for operating said playing actions; expression-governing means for varying the degree of power applied to said playing actions; a plurality of means operatively connected to said expression-governing means for producing respective changes in playing intensity; and a single means cooperable with each of said plurality to negative operation thereof.

23. An instrument of the character described comprising, in combination, playing actions; a main source of power for operating said playing actions; expression-governing means to vary the degree of power applied to said playing actions; a pneumatic device for governing said expression-governing means; a tracker; means governed from the tracker for exhausting said pneumatic device; and additional means separately governed from the tracker for controlling said pneumatic device with a pneumatic effect predominating said exhausting.

24. An instrument of the character described comprising, in combination, playing actions; a main source of power for operating said playing actions; expression-governing means to vary the degree of power applied to said playing actions; a valve and pneumatic governing device therefor, to

- govern the expression-governing means; means for bleeding said pneumatic device; and additional means for governing said pneumatic device with pneumatic effect predominating said bleeding. 5
25. An instrument of the character described comprising, in combination, playing actions; a main source of power for operating said playing actions; regulating means 10 operating intermediate said source of power and the playing actions; expression-governing means to vary the regulation by said regulating means, including a pneumatic device; means for bleeding said pneumatic device; and means to govern the pneumatic condition in said device to predominate said bleeding. 15
26. An instrument of the character described comprising, in combination, playing actions; a main source of power for operating said playing actions; regulating means 20 operating intermediate said source of power and the playing actions; a valve to vary the regulation by said regulating means; a pneumatic device to govern the valve; a tracker; means controlled from the tracker for bleeding said pneumatic device; and additional means separately controlled from the tracker for governing said pneumatic device with 25 pneumatic effect predominating said bleeding. 30
27. An instrument of the character described comprising, in combination, playing actions; a main source of power for operating said playing actions; regulating means 35 operating intermediate said source of power and the playing actions; a valve to vary the regulation of said regulating means; a pneumatic device to govern the valve; and opposed pneumatic means concurrently operable to control said pneumatic device, one said means when operated, predominating the other. 40
28. An instrument of the character described comprising, in combination, playing actions; a main source of power for operating said playing actions; expression-governing means to vary the degree of power applied to said playing actions; a pneumatic 45 device operatively connected to the expression-governing means for governing the same; and opposed pneumatic means concurrently operable to control said pneumatic device, one said means, when operated, predominating the other. 55
29. An instrument of the character described comprising, in combination, playing actions; a main source of power for operating said playing actions; and expression- 60 governing apparatus constructed and arranged to produce a crescendo and an incremental intensity change without interrupting the crescendo. 65
30. An instrument of the character described comprising, in combination, play- ing actions; a main source of power for operating said playing actions; an expression-governing apparatus constructed and arranged to produce a crescendo and to accent a note or notes during the crescendo. 70
31. In an apparatus of the character described, the combination of playing actions; a main source of power for operating said playing actions; expression governing means to vary by perceptible increments the degree 75 of power applied to the playing actions; a plurality of valve means for said expression governing means adapted each to establish an incremental change in the degree of power; a single valve means common to said plurality to negative the operation thereof; a tracker; connections from said valve means to the tracker; and a co-operating note sheet provided with note sounding perforations, a plurality of perforations for said plurality 80 of valve means and a single perforation for said single valve means common thereto. 85
32. In an apparatus of the character described, the combination of playing actions; a main source of power for operating said 90 playing actions; expression governing means to vary by perceptible increments the degree of power applied to the playing actions; a plurality of valve means for said expression governing means adapted each to 95 establish an incremental change in the degree of power; a single valve means common to said plurality to negative the operation thereof; a tracker; and a co-operating note sheet provided with the usual note sounding 100 perforations and expression controlling perforations including a plurality of expression setting perforations and an expression cancelling perforation. 105
33. In an apparatus of the character described, the combination of playing actions; a main source of power for operating said playing actions; expression governing means to vary by perceptible increments the degree of power applied to the playing actions; a 110 plurality of valve means for said expression governing means adapted each to establish an incremental change in the degree of power; a single valve means common to said plurality to negative the operation thereof; 115 a tracker; and a co-operating note sheet provided with the usual note sounding perforations and expression controlling perforations including a plurality of expression setting perforations, and an expression cancell- 120 ing perforation to negative the effect of any expression setting perforations not in alignment therewith transversely of the note sheet. 125
34. In an apparatus of the character described, the combination of playing actions; a main source of power for operating said playing actions; expression governing means to vary by perceptible increments the degree of power applied to the playing actions; a 130

- plurality of expression setting means operable singly or in combination to establish distinct grades of playing intensity; an expression cancelling means common to all said
- 5 expression setting means to negative the operation thereof; a tracker; connections from said expression setting and expression cancelling means to the tracker; and a note sheet provided with expression setting perforations and a single series of expression
- 10 cancelling perforations to negative the operation of all preceding expression setting perforations.
35. In an apparatus of the character described, the combination of playing actions; a main source of power for operating said playing actions; expression governing means to vary by perceptible increments the degree of power applied to the playing actions; a
- 15 plurality of expression setting means operable singly or in combination to establish distinct grades of playing intensity; an expression cancelling means common to all said expression setting means to negative the
- 20 operation thereof; a tracker; connections from said expression setting and expression cancelling means to the tracker; and a note sheet provided with a plurality of longitudinally extending series of expression setting perforations and a single longitudinally extending series of expression cancelling perforations, any expression cancelling perforation negativing the effect of all preceding expression setting perforations.
- 30 36. In an apparatus of the character described, the combination of playing actions; a main source of power for operating said playing actions; expression governing means to vary by perceptible increments the
- 35 degree of power applied to the playing actions; a plurality of expression setting means operable singly or in combination to establish distinct grades of playing intensity; an expression cancelling means common
- 40 to all said expression setting means to negative the operation thereof; a tracker; connections from said expression setting and expression cancelling means to the tracker; and a note sheet provided with a plurality
- 45 of longitudinally extending series of expression setting perforations and a single longitudinally extending series of expression cancelling perforations, any expression cancelling perforation being ineffective with respect to expression setting perforations in
- 50 transverse alignment therewith.
37. An instrument of the character described comprising, in combination, playing actions; a main source of power for operating said playing actions; expression governing means to vary the degree of power applied to said playing actions; a plurality of means operatively connected to said expression governing means to produce a plu-
- rality of incremental changes in playing intensity; a single means to negative operation of said plurality of means; a tracker; controlling means connecting each of said plurality of means and said single means with a corresponding tracker vent; and a note sheet provided with a plurality of series of perforations to control said plurality of means and a single series of perforations to control said single means.
38. An instrument of the character described comprising, in combination, playing actions; a main source of power for operating said playing actions; means for varying the degree of power applied to said playing actions; a tracker having a plurality of vents corresponding each to an incremental change in playing intensity and a single tracker vent corresponding to the reverse of all said incremental changes; means operatively connecting said tracker vents with the expression governing means; and a note sheet having a plurality of expression controlling perforations to produce said incremental changes by the opening of said plurality of tracker vents respectively and a single series of expression controlling perforations to produce reverse changes by the opening of said single tracker vent.
39. An instrument of the character described comprising, in combination, playing actions; a main source of power for operating said playing actions; means for varying the degree of power applied to said playing actions; a tracker having a plurality of vents corresponding each to an incremental change in playing intensity and a single tracker vent corresponding to the reverse of all said incremental changes; means operatively connecting said tracker vents with the expression governing means; and a note sheet having a plurality of expression controlling perforations to produce said incremental changes by the opening of said plurality of tracker vents respectively and a single series of expression controlling perforations to negative the effect of any one or all of the expression controlling perforations not in alignment therewith.
40. In a self-playing musical instrument, an expression-governing device including a pneumatic, a spring normally opening said pneumatic with a force sufficient to counteract that of the air tension therein necessary to produce a certain tone effect, separate pneumatics for opposing the action of said spring, and means for energizing said last-named pneumatics individually and collectively.
41. In a self-playing musical instrument, the combination with a wind-inducing device having means for communication with a sound-producing action, of means subject to operation by the air tension of said device

- for throttling such communication, and a spring opposing the operation of the last-named means with a force substantially equal to that of the air-tension required to 5 produce loud tone effects.
42. In a self-playing musical instrument a pneumatic having means for communication with a wind-inducing device and a sound-producing action and subject to operation by 10 air tension therein, means actuated by said pneumatic for throttling communication with the sound-producing action, and a spring opposing the action of said pneumatic under a force substantially equal to that of 15 the air tension required to produce loud tone effects.
43. In an automatic musical instrument the combination of a plurality of pneumatic control devices, a plurality of valve mechanisms for said pneumatic devices, a tracker, means connecting each of said valve mechanisms with the tracker whereby the same may be separately operated, a valve mechanism common to all said control devices and 20 means connecting the same with the tracker whereby said devices may be jointly operated from the tracker.
44. In an automatic musical instrument the combination of a plurality of pneumatically controlled devices; a plurality of valve 25 mechanisms separately operable to govern individually the said devices, means for separately controlling said plurality of valve mechanisms; and another valve mechanism
- for controlling said plurality of valve mechanisms. 35
45. In an automatic musical instrument the combination of a plurality of pneumatically controlled devices; a tracker; a valve mechanism for each of said plurality of devices and each having connection with a corresponding tracker vent; a single valve mechanism having connection with said plurality of valve mechanisms and also a connection with a single tracker vent; a control 40 sheet having a plurality of series of perforations to operate said plurality of valve mechanisms and a single series of perforations to negative the effect of any selected perforation in any one of said series. 45
46. Expression controlling mechanism for a pneumatically operated musical instrument comprising, in combination, a pneumatically controlled regulating device, controlling means therefor to produce a plurality of playing intensities differing from one another by perceptible increments, and additional concurrently operable controlling means to vary the expression effects produced by operation of the first mentioned 50 controlling means. 55

In testimony whereof, I have signed my name to this specification, in the presence of two subscribing witnesses.

CHARLES F. STODDARD.
